US00D431867S

United States Patent [19]

Maynard et al.

[11] Patent Number: Des. 431,867

[45] Date of Patent: ** Oct. 10, 2000

[54] IMMUNOASSAY TEST DEVICE

[75] Inventors: **James E. Maynard; Mark A. Crosby**, both of Boulder, Colo.; **Alan J. Fujii**, Newport Beach, Calif.

[73] Assignee: **Biostar, Incorporated**, Boulder, Colo.

[**] Term: 14 Years

[21] Appl. No.: 29/102,418

[22] Filed: Mar. 22, 1999

[51] LOC (7) Cl. 24-02

Primary Examiner—Ian Simmons

[57] CLAIM

The ornamental design for an immunoassay test device, substantially as shown and described.

DESCRIPTION

FIG. 1 is a top, front perspective view of an immunoassay test kit;

FIG. 2 is a top plan view thereof;

FIG. 3 is a bottom plan view thereof;

FIG. 4 is a side elevational view thereof;

FIG. 5 is front elevational view thereof; and,

FIG. 6 is a rear elevational view thereof.
